REFRIGERATION

Bennet Carroll Shipman, deceased, late of Arlington County, Va., by Clara Wood Shipman, executrix, Birmingham, Ala., assignor to Servel, Inc., New York, N. Y., a corporation of Delaware

Application November 19, 1938, Serial No. 241,372

4 Claims. (Cl. 62—8)

This invention relates to refrigeration and it is an object of the invention to provide for heat transfer from a plurality of refrigerators to a source of refrigeration located at a lower level.

The drawing shows a refrigeration transfer system embodying the invention. At an upper level, for instance, the business floor of a meat market, delicatessen, restaurant, or like establishment, are three refrigerators, a large walk-in type cooler 10, a display case 11, and a small cooler 12. In the upper part of walk-in cooler 10 is a cooling coil 13 provided with a header 14. In the display case 11 is a cooling coil 15 provided with a header or accumulator 16. In the small refrigerator 12 is a cooling coil 17 provided with a header or accumulator 18. At a lower level, for instance, the basement of the store, is a refrigeration apparatus of which only the evaporator 19 is illustrated. The refrigeration apparatus may be like that described in application Serial No. 107,852 of Albert R. Thomas.

In the evaporator 19 is a coil 20 which will be referred to as a condenser coil. Above the coil 20 is a liquid distributor 22. Liquid refrigerant enters evaporator 19 through a conduit 23. The liquid enters the distributor 22 and thence is distributed onto the top of the coil 20. The liquid descends over the outer surface of coil 20, evaporating and diffusing into inert gas in the evaporator, producing a refrigeration effect for cooling fluid on the inside of coil 20. Inert gas enters the upper part of evaporator 19 through conduit 24 and tube 25. The mixture of gas and vapor leaves the lower part of the evaporator through conduit 26.

Above the walk-in cooler 10 is a separating vessel 27. The bottom of vessel 27 is connected by a conduit 28 to the lower part of header 14. The top of vessel 27 is connected by a conduit 29 to the upper end of condenser coil 20. The lower end of condenser coil 20 is connected by a conduit 30 to the lower part of a vapor lift vessel 31. The upper part of vessel 31 is connected by a conduit 32 to an intermediate part of separation vessel 27. The conduit 33 is connected by a T 33a to the upper part of conduit 32. The other end of conduit 33 is connected to branch conduits 34 and 35. Conduit 34 is connected to the lower part of header 16 in the display case 11. Conduit 35 is connected to the lower part of header 18 in the small refrigerator 12. The evaporator 19, vapor lift vessel 31, conduits 30 and 32, separation vessel 27, and conduits 28, 33, 34, and 35 are thermally insulated.

In the vapor lift vessel 31 is an upward directed

nozzle 36. The nozzle 36 is connected in parallel to the headers 14, 16 and 18 by a conduit 37 and branching conduits 38, 39, 40 and 41. Conduit 38 is connected to the upper part of header 14. Conduit 40 is connected to the upper part of header 16. Conduit 41 is connected to the upper part of header 18.

In conduit 34 there is a control valve 42 similar to an expansion valve. Valve 42 is 10 thermostatically operated responsive to temperature at the thermostat bulb 43 which is in thermal contact with conduit 40 adjacent header 16. A similar thermostatic valve 44 in conduit 35 operates responsive to temperature at bulb 45 attached to conduit 41 adjacent header 18.

The above described system is evacuated and charged with a suitable heat transfer fluid such as methyl chloride. When the refrigeration apparatus in the basement is started, the evaporator 19 reduces the temperature of condenser coil 20 so that vapor condenses to liquid in this coil and flows downward into conduit 30, vessel 31, and the lower parts of conduits 32 and 37. Collapse of vapor in coil 20 causes a reduction in pressure 25 in conduit 29, separation vessel 27, and the upper end of conduit 32. Due to the pressure difference in the system brought about by the reduction in pressure in said parts, vapor in conduit 37 at the higher pressure forces liquid downward in the lower part of conduit 37 until the vapor issues from nozzle 36. This vapor bubbles into liquid 30 in vessel 31 and rises in conduit 32. Liquid is carried upward by vapor in conduit 32 and vapor and liquid issue from the upper end of conduit 32 35 in separation vessel 27. Liquid also enters conduit 33 at the T 33a and fills conduit 33 and branch conduits 34 and 35. The vapor flows from separation vessel 27 through conduit 29 back to the condenser coil 20. Liquid flows from 40 separation vessel 27 through conduit 28 into header 14 and cooling coil 13 in the walk-in cooler 10. Liquid flows from conduit 34 into header 16 and coil 15 in the display case 11. Liquid flows from conduit 35 into header 18 and coil 17 in the 45 small refrigerator 12. In the several coils 13, 15 and 17, liquid evaporates to produce cooling of the several refrigerators. The resulting vapor flows through the previously described vapor conduits into conduit 37 and thence to the nozzle 36 50 in the vapor lift vessel 31.

In operation of the system, a column of liquid stands in conduit 30 at a height H above the nozzle 36. This column of liquid is kept supplied from the condenser coil 20. Conduit 32 55 contains a column of gas and liquid. This col-

umn goes upward as liquid is supplied to conduit 30 and gas issues from nozzle 36 so that gas and liquid issue from the upper end of conduit 32. In conduit 28 and separation vessel 27, there stands a column of liquid H_1 above the surface level of liquid in header 14. The apparatus is constructed so that H_1 can be equal to or slightly greater than H . These liquid columns may be referred to as reaction heads for the vapor liquid lift column 32. A column of liquid also stands in conduit 33 above the surface level of liquid in the header 18. This column should be at least equal to column H_1 . The system should be constructed so that this column may be appreciably greater than H_1 to provide extra head for causing flow through the valves 42 and 44. The liquid column in conduit 33 backs up to the T 33a.

The valves 42 and 44 are constructed to move toward their closed positions upon decrease in temperature and move toward their open positions upon increase in temperature. These valves control flow of liquid through conduits 34 and 35 into the cooling coils 15 and 17 respectively. The valves 42 and 44 may be adjusted to maintain different temperatures in the respective refrigerators.

Various changes may be made within the scope of the invention which is not limited except as indicated in the following claims.

What is claimed is:

1. In a method of heat transfer including evaporation of heat transfer fluid at an upper level, condensation of the fluid to liquid at a lower level, and raising liquid upward from said lower level, that improvement which consists in carrying out evaporation at a plurality of upper levels, utilizing vapor resulting from said evaporation to cause said raising of liquid upward from said lower level, conducting raised liquid to said upper levels by gravity flow, and control-

ling flow of liquid to a lower one of said upper levels responsive to a temperature condition affected by evaporation at that level.

2. In a method of heat transfer including evaporation of heat transfer fluid at an upper level, condensation of the fluid to liquid at a lower level, and raising of liquid between said levels by means of vapor produced at the upper level, that improvement which consists in carrying out evaporation at a plurality of upper levels, causing said raising of liquid by vapor lift action of vapor produced at said upper levels, and utilizing the difference in said upper levels to form a liquid column to act against the pressure of vapor at a lower one of said upper levels.

3. A circuit for heat transfer fluid including a place of condensation, a plurality of places of evaporation above said place of condensation, vapor operated means for raising liquid upward from said place of condensation, conduit means for receiving in parallel vapor from said places of evaporation and conducting the vapor to said liquid raising means, and conduits for conducting raised liquid by gravity to said places of evaporation in parallel and arranged to provide liquid columns for acting against the pressure of said vapor.

4. A circuit for heat transfer fluid including a place of condensation, a plurality of places of evaporation at different levels above said place of condensation, means operated by pressure of vapor in the circuit for raising liquid upward from said place of condensation, conduits for conducting raised liquid by gravity to said places of evaporation, and temperature responsive means for controlling flow of liquid to a lower one of said places of evaporation.
